OUTBOARD MOTOR CONTROL

Finn T. Irgens, Milwaukee, Wis., assignor to
Outboard Motors Corporation, Milwaukee,
Wis., a corporation of Michigan

Application November 8, 1929. Serial No. 405,561

1 Claim. (Cl. 115—17)

This invention relates to improvements in outboard motor controls.

It is one of the primary objects of the invention to provide a centralized control for an outboard motor whereby all control devices necessary for the operation of the motor are associated with the tiller by which the motor is turned or the boat to which the motor is applied is guided. In accordance with this invention the tiller is equipped not only with an ignition control device or magneto grounding switch but also with a carbureter control member which combines the functions of throttling and choking.

It is very important to the present invention that the several controls above mentioned are so disposed on the tiller as to leave the grip portion thereof entirely free and unencumbered. It is very desirable to provide a rotary control handle because such a control is manipulated naturally by most operators. If such rotary handle be employed also as a tiller grip, however, the arrangement is objectionable in that the operator will unconsciously rotate the grip in manipulating the tiller. It is, therefore, an important object of the invention to provide a carburetion and mixture control in the form of a sleeve mounted on the tiller handle in a position offset from the normally engaged grip portion of such handle but within reach of the operator's hand so that it may be manipulated without releasing the tiller.

Another object of the invention relates to the means through which control of the engine is effected. In this particular it is my purpose to provide a manifold system which includes a plurality of manifold passages leading from the carbureter to the engine. In the two cycle, two cylinder engine disclosed both of these passages lead to the crank case. Each is controlled in the usual way by the piston in the particular cylinder through which the respective passage communicates with the crank case.

The chief purpose in providing a multiplicity of manifold passages is to maintain more efficient atomization of fuel by keeping a more constant flow of mixture through each given manifold passage which is in operation during the throttling of the engine. Instead of reducing the amount of mixture admitted to a single passage I am able, by the invention herein disclosed, successively to cut off a series of passages whereby the remaining passage will in any given case retain high mixture velocity which will prevent the settling or deposit of atomized fuel on the wall of the manifold.

Another advantage of the dual manifold arrangement herein disclosed consists in the fact that a modern high speed two cycle engine effects compression as far as possible in the lower ends of the cylinders, the crank case being filled as far as possible with the crank and associated parts. When the engine is running throttled such parts do not materially interfere with the transfer of the gas from one cylinder to another through the crank case. When the engine is running at full capacity charges of gas are delivered by the several manifolds directly to the preliminary compression space in the cylinders in which the gas is ultimately consumed.

In the drawing:

Figure 1 is a perspective view in elevation of an outboard motor embodying the invention.

Figure 2 is a detail view in partial section through the carbureter mixing chamber and manifold system.

Figure 3 is a detail in cross section through the mixture control device.

Like parts are identified by the same reference characters throughout the several views.

The outboard motor shown comprises a bracket 5 having a bearing sleeve 6 in which the motor assembly is unitarily dirigible. The drive shaft housing sleeve 7 connects the submersible lower unit 8 with the engine which includes cylinders 9 and 10, magneto fly wheel 11, fuel tank 12 and a carbureter including float chamber 13, mixing and control chamber 14, air inlet 15 and manifolds 16 and 17.

A bracket 20 secured to the engine provides a pivot at 21 upon which the tiller grip 22 is mounted to swing upwardly from the position in which it is illustrated, this arrangement being common practice. It is also common to provide in the tiller grip a push button 23 for grounding the magneto to interrupt the ignition when it is desired to stop the engine suddenly. This arrangement is such that the operator grasping the tiller grip 22 will have full control of the rotative or angular position of the motor in its bearing sleeve 6 while keeping the button 23 immediately under his thumb.

Mounted on the tiller immediately behind the grip portion 22 thereof is a throttle and choke control in the form of sleeve 25 which, for convenient manipulation, may be provided with 105 knurling at 26. It will be obvious that without releasing the tiller the operator can slide his hand rearwardly to engage sleeve 25 and can thereby manipulate the throttle or choke through mechanism hereinafter to be described.

An arm 27 mounted on the sleeve 25 is universally connected at 28 with a rod or link which at its other end is pivotally connected at 30 to the carburetor control disc 31. This disc 5 is rotatable on the front of the control and mixing chamber 14 above referred to and is connected to impart rotative movement to a segment shaped valve member 35 which is mounted to rotate within a cylinder portion of chamber 10 14.

Figure 2 shows the valve in the normal intermediate position which it occupies when the engine is operating at full capacity. If rotated in a clockwise direction from position in which valve member 35 is shown this member may be used to cut off the air admission port 15 to any desired degree. If oscillated in a counterclockwise direction from the position in which it is illustrated in Figure 2 the valve member 35 may obviously 15 be used to cut off manifold 16 to any desired degree and subsequently to cut off manifold 17 to any desired degree. Regardless of the number 20 of manifold passages employed, a valve such as that shown will move across them successively so that the resulting constriction of any given 25 passage will be low as compared with the total area available for the flow of mixture. Thus high mixture velocity will be maintained in any passage not yet cut off by the manipulation of valve 35.

Since, in the particular device herein disclosed, the manifold passages 16 and 17 lead to the inner 30 ends of respective cylinders which are in communication with each other the result will be to supply mixture to both cylinders regardless of whether one manifold is completely cut off and the mixture will be more uniform than would be the case if the velocity of flow were permitted to drop through throttling a single and relatively 35 large manifold passage.

A fuel duct 36 leads from the float chamber 13 to a nozzle 37 located in the convex wall portion 38 of the mixing and control chamber 14. This disposition of the nozzle within the arc traversed 40 by the valve 35 makes possible the use of a single valve member for both choking and throttling effects as above described. It leaves the nozzle 45 fully exposed to such air as flows through the mix-

ing chamber when valve 35 is used for throttling and it leaves the nozzle exposed to depressions produced in the mixing chamber by the operation of the engine when the valve 35 is moved across the air inlet 15 for choking. Preferably the valve 35 is provided with a port at 39 of such diameter as to admit enough mixture to the last manifold closed by the valve so that the engine will idle. This port is located near the edge of the valve which leads in its counterclockwise throttling movement so that the port is not exposed when the valve is used as a choke. 80 85

Because of the control assembly above described it will be obvious that the operator of an outboard motor equipped in accordance with the disclosure herein can control the entire operation of the motor as well as accomplish steering of the boat to which the motor is applied with the use of a single hand. At the same time the operator is relieved of the burden of maintaining the throttle and choke control in any given setting. The arrangement is such that these parts will remain in any position to which they have been 90 adjusted and due to the disposition of sleeve 25 in off set relation to the tiller grip 22 there is no danger of inadvertent manipulation of the control parts. Sleeve 25 constitutes in effect an auxiliary grip for the tiller which is effected to maintain tiller control even while manipulation 95 to control an engine function. 100 105

I claim:

The combination with an outboard motor structure dirigibly mounted, of a tiller pivotally connected with said structure for hinged movement in an upright plane with respect thereto while available in all positions for dirigible control thereof, said tiller having a relatively fixed portion and a relatively movable coaxial portion, a lever carried by the movable portion of the tiller adjacent the fulcrum of its hinged movement, an engine control spaced laterally from said tiller and provided with a lever arm and an inflexible link pivoted between the first and second mentioned levers for the operative transmission of movement to said control irrespective of the hinged adjustment of the tiller. 110 115 120
